UNITED STATES PATENT OFFICE.

ENOCH M. FREDERICKS, OF CHICAGO, ILLINOIS.

DESIGN FOR A SUPPORTING-PIECE OR PLUNGER FOR DENTAL CHAIRS.

SPECIFICATION forming part of Design No. 30,693, dated May 2, 1899.

Application filed April 5, 1899. Serial No. 711,871. Term of patent 14 years.

To all whom it may concern:

Be it known that I, ENOCH M. FREDERICKS, a citizen of the United States, residing at Chicago, in the county of Cook and State of Illinois, have invented and produced a new and original Design for Supporting-Pieces or Plungers for Dental Chairs, of which the following is a specification, reference being had to the accompanying drawings, forming part thereof.

Figure 1 is a perspective view of a supporting-piece or plunger, showing my new design. Fig. 2 is a vertical sectional view taken on line 2 2 of Fig. 1, and Fig. 3 is a cross-sectional view taken on line 3 3 of Fig. 1.

As shown in the accompanying drawings, the leading or material feature of my design consists of a hollow piece or plunger A of substantially an elliptic-lanceolate form in cross-section. This piece is provided on its inner

surface, near one of its ends, with recesses or 20 cavities a and a', which extend some distance longitudinally with the piece or plunger and, as is clearly shown in Fig. 3 of the drawings, on each side of the apices thereof. The piece A is provided near one of its ends with a series of openings b, which communicate with one of the cavities a or a' on its inner surface. 25

Having described my invention, what I claim as new, and desire to secure by Letters Patent, is—

The design for a supporting-piece or plunger for dental chairs, substantially as herein shown and described.

ENOCH M. FREDERICKS.
